UNITED STATES PATENT OFFICE

ERNST WILLHEIM, OF GILGENBERG, AUSTRIA

CONTROL APPARATUS

Application filed January 25, 1927, Serial No. 163,513, and in Austria February 1, 1926.

The invention relates to a control apparatus serving mainly but not exclusively for controlling autocars by indicating whether or not the car had been used during the absence 5 of the owner without authorization. Moreover on touring the net travelling time may be read from such apparatus.

The present invention aims at improving a controlling apparatus in such manner, that 10 for initiating its function no connection whatever with any part or member of the car is required and that consequently putting the clock out of work is impossible. According to the present invention this is realized by a 15 wheel work combined with a dial work or by a clock, the function of which is only possible during the action of the external forces (shaking or jolting movements), to which the car is exposed owing to the unevenness of the 20 road, alterations of the speed or in taking curves. The arrangement may be such, that a clock to be wound up in normal fashion is provided with a locking device, which during the running of the car is kept out of action by 25 the said forces. But in addition thereto also the winding up may in a known manner be effected by these forces, for which purpose the driving member of the clock mechanism is connected to a weight mounted in such manner, that it is capable of oscillating. In any 30 of these cases the clock differs from ordinary clocks or watches also in that the hands can only be moved by the wheel work, but not from outside.

35 In the annexed drawing by way of example an embodiment of the invention is illustrated, Fig. 1 being a side elevation with part of the casing being taken off and Fig. 2 a sectional view taken on the line a—a of Fig. 1.

40 Between the plates 1 and 2 a clock work of normal construction is mounted and between the plate 2 and the base plate 3 the devices are placed, by which the clock is kept working during the running periods of the car. 4 45 is the axle of that clock wheel, which acts on the driving spring thereof. To this axle, turning in a bearing of the base plate 3 and passing through the plate 2, a ratchet wheel 5 is secured, with which engages the pawl 6 50 of a lever 7 rotatably mounted on said axle.

The free end of this lever 7 is so formed as to constitute a guide for a pin 8 of the slide rod 10 guided by the bearings 9. To the one end of the rod a thin cord 12 or like flexible member is fastened, bearing a weight 14, which cord or string is maintained in the state of tension by the two springs 11 and 13. When the car is shaken by passing over uneven places of the road, by altering its speed or by taking curves, the weight is caused to oscillate, which movement is by the slide rod 10 transferred to the lever 7 winding up the driving spring of the clock. 55

15 is a catch hook stopping the clock at the still-stand of the car by engaging with 60 one of the clock wheels, for instance with the swing wheel (balance escapement) 16, thus impeding its rotation. The hook 15 is pivotally mounted on an axle 15^a and tends to swing towards the wheel 16 under the influence of a spring 17 acting on the hook. Near the pivot a thread 18 or similar flexible member is connected to the hook, which thread is kept tensioned by the spring 17 acting on the hook. This thread passes through eyelets 70 19, 20 provided on wires 21, 22. The latter are kept under tension by springs 23, 24 and 23^a, 24^a respectively and are provided with masses 25 and 26 of different weight. If desired, also the springs 23, 24 may be of different strength and tension. The springs are made of very thin wire and the said weights 25, 26 are relatively very light, so that very small forces are sufficient for causing the springs to oscillate. But as the weights and 85 the tension of the springs are unequal, the oscillations will be asynchronous. Consequently during the run of the car the eyelets 19, 20 will never be simultaneously in the position which they are occupying when at rest 90 during the stillstand of the car. The thread 18 is therefore bent at the places where it passes through the eyelets in various, permanently changing forms and subjected to a braking action, whereby the hook 15 is kept 95 out of engagement with the swinging wheel 16.

100 A special device locking the clock may be dispensed with if means are provided preventing the driving spring of the clock being

5 tensioned above a certain limit. This highest tension ought to be relatively small and only sufficient to keep the clock working during a few, say for instance 3 minutes. In such case the clock will go on for 3 minutes after the car has been stopped, and for certain purposes such inexactness of the clock reading may be admitted.

10 The result that the driving spring of the clock cannot be wound up above a certain tension, can easily be realized by making the lever arm 7^a from a plate spring, which is bending when the driving spring has attained the allowed maximum of tension, or 15 else a driving spring may be used, the one end of which is movably connected either to the casing or to the axle so that it can only be wound up to a certain degree of tension.

20 In any case the hand work must be protected in such manner, that the position of the hands 35 cannot be changed from outside. If a normal clock work is used, the means for moving the hands must therefore be omitted. Moreover it must be impossible to obtain access to the clock work or gearing and to the hands 35 without visible violation of leaden seals to be applied to the controlling device. For this purpose the clock casing 27 may be secured to the car e. g. to the frame or board 25 carrying the fittings by means of screws 30 and a string 30 may pass therethrough, which string is sealed by means of leaden seals 31.

35 The clock glass is not kept in position in the usual manner by the aperture of the casing, but by a rim 32 thereof bent at an angle and having as well as the glass 33 to be inserted a greater diameter than that of the opening 34, so that the glass can only be put 40 in place from inside.

What I claim is:

1. An apparatus for controlling the running time of vehicles, consisting of a clock, having clockworks, a movable locking device 45 adapted to engage an element of the clockworks and when so engaged preventing the working of the clock, resiliently supported masses, adapted to oscillate under the influence of motion of their support and means 50 translating the movement of said masses to said locking device to move and retain the locking member out of reach of the element of the clockworks.

55 2. An apparatus for controlling the running time of vehicles, consisting of a clock having clockworks, a movable locking hook engaging one of the wheels of the clockworks to prevent the running of the clock, and resiliently suspended masses adapted to be kept 60 in oscillating motion by the movement of the vehicle, and means connecting said masses to said movable hook for maintaining the locking hook in a withdrawn, ineffective position during the time the vehicle is running.

65 3. An apparatus for controlling the run-

ning time of vehicles, consisting of a clock having clockworks, a movable locking hook, engaging with one of the wheels of the clockworks to prevent the running of said clock, two resiliently suspended masses adapted to be kept in oscillating motion by the movement of the vehicle, members secured to these masses and provided with eyelets, and a flexible threadlike member passing through the eyelets, which latter member is at the one end fastened to a fixed point and by the other to the movable locking hook.

In testimony whereof I have affixed my signature.
